CLAIM

The ornamental design for a digital camera, as shown and described.

DESCRIPTION

FIG. 1 is a bottom, left perspective view of a digital camera showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is a bottom, left perspective view of the digital camera showing the display in an open state.

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a bottom, left perspective view of the digital camera showing the display in an alternate open state;

FIG. 16 is a front view thereof;

FIG. 17 is a rear view thereof;

FIG. 18 is a right side view thereof;

FIG. 19 is a left side view thereof;

FIG. 20 is a top view thereof;

FIG. 21 is a bottom view thereof;

FIG. 22 is an enlarged view of the claimed portion of FIG. 11; and,

FIG. 23 is an enlarged view of the claimed portion of FIG. 15.

The broken lines shown in the drawings depict portions of the digital camera that form no part of the claimed design.

1 Claim, 23 Drawing Sheets
